DESIGN FOR A LATHER'S TOOL HEAD

Charles F. Griffith, Merion, Pa.

Application August 23, 1939, Serial No. 86,856

Term of patent 7 years

To all whom it may concern:

Be it known that I, Charles F. Griffith, a citizen of the United States, residing in Merion, Montgomery County, Pennsylvania, have invented a new, original, and ornamental Design for a Lather's Tool Head, of which the following is a specification, reference being had to the accompanying drawing, forming part thereof, in which:

Figure 1 is a plan view of a lather's tool head showing my new design, and
Fig. 2 is a side elevation thereof.

I claim:

The ornamental design for a lather's tool head, substantially as shown.

CHARLES F. GRIFFITH.
